REFRIGERATOR CABINET

Albert P. Ball, Detroit, Mich., assignor to Briggs Manufacturing Company, Detroit, Mich., a corporation of Michigan

Application October 7, 1933, Serial No. 692,560

7 Claims. (Cl. 62—89)

This invention relates to refrigerator cabinets and more particularly to cabinets useful in ice-less refrigerating systems.

An object of the invention is to provide an improved refrigerator cabinet having a main or inner storage compartment and a supplementary or outer compartment formed by means of a casing hinged therein and accessible when the main cabinet door is open, said casing being mounted to swing through the door opening to permit access to the main compartment.

A further object of the invention is to provide a refrigerator cabinet of the foregoing type having improved means for maintaining the temperature and air within the supplementary compartment in desirable condition for the storage of certain foods, permitting the segregation of foods with high water content and preventing contamination of foods stored in the main or inner compartment.

Other objects of this invention will appear in the following description and appended claims, reference being had to the accompanying drawings forming a part of this specification wherein like reference characters designate corresponding parts in the several views.

Fig. 1 is a front elevation, partly broken away, illustrating a refrigerator cabinet embodying the invention.

Fig. 2 is a fragmentary horizontal section taken substantially along line 2—2 of Fig. 1 in the direction of the arrows.

Fig. 3 is a detail section taken through line 3—3 of Fig. 1 in the direction of the arrows.

Fig. 4 is a fragmentary perspective view illustrating a removable tray for the supplementary compartment.

Fig. 5 is a fragmentary vertical section taken substantially through lines 5—5 of Fig. 1 in the direction of the arrows.

Fig. 6 is a fragmentary horizontal section illustrating a modification.

Fig. 7 is a fragmentary horizontal section illustrating a further modification.

Before explaining in detail the present invention it is to be understood that the invention is not limited in its application to the details of construction and arrangement of parts illustrated in the accompanying drawings, since the invention is capable of other embodiments and of being practiced or carried out in various ways.

Also it is to be understood that the phraseology or terminology employed herein is for the purpose of description and not of limitation, and it is

not intended to limit the invention claimed herein beyond the requirements of the prior art.

Referring to the drawings wherein several present preferred adaptations of the invention are illustrated by way of example, there is shown at 10 a suitable refrigerator cabinet of any desired conventional construction having enclosing walls which may be of composite formation composed of insulating material and outer and inner metal sheathing. The front of the cabinet has the usual door opening controlled by a door 11 hinged at 12 to the front wall of the cabinet. The door may also be a conventional construction including insulating material sheathed between outer and inner panels.

In accordance with the present invention there is mounted within the main compartment of the cabinet a casing member, generally indicated at 13, which forms a supplementary compartment.

The casing 13 may be formed from sheet metal and comprises a vertical back wall 14, forwardly extending sides 15, and forwardly extending top and bottom walls 16 and 17, respectively. A box-like casing is thus provided which is open at its front facing the main cabinet door 11. This casing member is preferably hinged within the cabinet to the top and bottom walls thereof at points rearwardly of the jamb faces of the door opening, see Fig. 5. In the present instance there is fixed to the bottom wall 17 of the casing 13, adjacent the hinged edge of the door 11, a depending pivot pin 18 which is adapted to seat in a recess or socket 19 provided in the base of the main cabinet, the pin 18 being rotatable within the socket or recess. Vertically aligned with the pivot pin 18 is a retractable pivot pin 20 carried by the top wall 16 of the casing member.

Threaded to the upper end of the pin 20 is an annular head 21 adapted to project into a circular socket or recess 22 in the top wall of the cabinet. The upper wall 16 is formed with a bearing boss 23 slidably receiving the pin 20, and mounted over this boss and engaging the head 21 is a compression spring 24. The pivot pin 20 is thus in the form of a retractable plunger having at its lower end a knob 25 which may be grasped to retract the plunger from its bearing socket or seat 22. In this manner the casing 13 may be readily removed from within the main compartment, whereas when in position within the compartment the pivots will be held within their respective sockets under sufficient spring pressure to prevent chattering or rattling of the casing during operation of the refrigerator mechanism.

It will be seen that the casing 13 is pivoted ad-

- 5 jacent one edge of the door opening, preferably at the same side of the cabinet as the hinge 13 for the main door 11, so as to swing outwardly through the opening when the door 11 is open.
- 10 5 The casing, therefore, provides substantially a supplementary door adapted to swing outwardly in the same direction as the main door so as to provide access to the interior of the cabinet. Means is preferably provided for locking the casing 10 or supplementary door 13 in its inner closed position, and also for limiting its inward swinging movement so that it may be held in proper position with relation to the outer door when the latter is closed. In the present instance the 15 compartment door or casing 13 is yieldingly held in closed position by means of a flat spring 26 having one end bolted at 27 to the cabinet wall. This spring is bowed in its length and flanged at its free end 28. When the compartment door 20 13 is swung into closed position, see Fig. 2, the spring will be compressed by engagement of the wall 15 with the normally flared side 29 of the spring, and inward movement of the door will be limited by the stop 28 of the spring. One or more 25 of the springs 26 may be provided for engagement with the compartment door 13 at different points in its height, and by this construction the member 13 will be yieldingly clamped and locked when closed so as to prevent vibration thereof.
- 30 30 In the embodiment illustrated in Figs. 2 and 5 the casing or compartment member 13 cooperates with the cabinet walls so as to effect a seal around the marginal edges of the main door opening. In this form of the invention the forward marginal edges of the casing 13 along the sides, top and bottom thereof are pressed to provide a rolled edge 30 forming an internal groove or channel within which is anchored the beaded edge 31 of a sealing strip which may be composed of rubber 35 or other suitable material. This strip has a projecting flexible lip 32 extending continuously around the marginal rolled edges 30 of the casing and positioned so as to contact with the rear marginal edge of the jamb face 33 of the cabinet. 40 45 Thus, as will be seen in Figs. 2 and 5, the sealing strip 31 effects a seal of the door opening around its inner edges, thereby providing a sealing means supplementary to the outer seal 11a. At the same time the strip 31 seals or closes off the open side 50 of the casing 13 from the main compartment.
- 55 Referring to Figs. 1 and 2 it will be noted that the casing 13 also functions as a closure means for the front opening of the evaporator casing. There is illustrated at 34 any conventional type of evaporator casing or housing which may include inner and outer walls 35 and 36 spaced for the reception of coiled piping or other conduits (not shown) through which the refrigerant flows. The evaporator 34 provides the usual sharp freezing compartment 37 within which are located ice trays 38. The front of the evaporator casing is open to permit removal of the ice trays and in the present instance this opening is controlled by means of the rear wall 14 of the casing 13, so 60 65 that when the casing or compartment 13 is swung into closed position within the main refrigerator compartment it will seal the front opening of the evaporator casing. In the present instance the front marginal wall of the evaporator casing is 70 75 formed with a continuous groove or channel 39 within which is anchored the beaded edge 40 of a sealing strip 41 composed of rubber or other suitable material. The strip 41 forms a projecting flexible lip in position to be engaged by the back wall 14 of the casing 13, and since the seal-

ing strip extends around the marginal edges of the front opening of the evaporator casing 34, the ice tray compartment thereof will be sealed when the casing 13 is in its closed position.

5 The interior of the supplementary compartment or casing 13 is provided with suitable shelving so that articles of food may be conveniently carried therein. In the present example a series of shelves 42 of wire formed basket type are detachably mounted within the casing. Each 10 shelf is suitably formed of lengths of wire 43, see Fig. 4, and secured thereto are vertical end plates 44. Each metal plate is formed with a vertical slot 45 and an extended portion 44a in rear of the slot. Secured to the side walls 15 of the casing 15 are pairs of aligned studs or pins 46 adapted to fit into the slots 45 and support the shelves in position within the casing. Each shelf 42 may be installed by tilting its rear part upwardly so as to insert and locate the studs 46 in the slots 45. 20 Thereupon the shelf is forced downwardly into horizontal position. During this action the end plates 44 will wedge between the side walls 15 of the casing and will yieldingly grip these walls. Thus the plates 44 will exert a sufficient degree 25 of spring pressure to hold the tray firmly in position against any danger of vibration or chattering during operation of the refrigerator mechanism.

30 It will be noted that the sealing strip 41 will not only effect a relatively tight closure of the front of the evaporator, or ice tray housing, but will also act as cushioning means and a yielding stop effective to exert sufficient pressure against the back wall of the casing so as to prevent objectionable noises due to vibration or chattering.

35 In the embodiment illustrated in Fig. 6 the construction is preferably substantially the same as above described with the exception that a modified type of seal between the supplementary 40 compartment and main cabinet is provided. In this instance there is anchored within the channel of the rolled edge 30 of the casing the beaded edge of a sealing strip 47 composed of rubber or other suitable material. This strip has a projecting flexible and compressible lip 48 adapted to engage at 49 the inner edge of the jamb face 33 when the casing 13 is swung into closed position. Moreover, the sealing lip 48 is so positioned as to be engaged by the inner edge 50 of the 50 door 11 when closed. Thus the weather strip 48 not only effects a seal between the jamb faces 11b and 33 of the door and cabinet, respectively, but also seals the open side of the compartment 13 from the interior or main compartment of the refrigerator.

55 In the embodiment illustrated in Fig. 7 the construction is also substantially the same as that heretofore described with the exception that a still further modification in the manner of sealing the supplementary compartment is provided. In this instance the beaded edge 51 of a sealing strip, composed of rubber or other suitable material, is also anchored within the channel formed by the rolled edge 30 of the casing. This 65 strip has a flexible projecting lip 52 inclinedly positioned so as to be engaged as at 53 by the rear face of the door 11 adjacent the marginal edges thereof. In this manner compartment 13 is sealed around its edge at the open side thereof 70 against the circulation of refrigerated air through the gap between the front edges of the supplementary compartment and the rear wall of the main door.

75 From the foregoing it will be seen that the 75

casing 13 provides a supplementary compartment accessible when the main cabinet door is open. Moreover, this compartment provides substantially an inner door capable of preventing any material exchange of air between the outside atmosphere and inner compartment when the outer door is open. This outer compartment is preferably maintained at a somewhat higher temperature than the main compartment, such as at a differential of approximately 10° F., and is, therefore, adapted for the storage of foods, such as fruits and vegetables, which should not be chilled to temperatures ordinarily maintained in the cabinet. The supplementary compartment is particularly advantageous for storing fruits and vegetables to prevent dehydration thereof since there is preferably substantially no circulation of refrigerated air from the main compartment through the supplementary compartment. When thus utilized to minimize dehydration of foods it is desirable that an exchange of air be provided between the compartments so as to prevent sweating, and this may be accomplished by providing a suitable number of small ventilating openings in the rear wall 14, preferably near the top thereof. If it is desired, however, to induce a circulation of refrigerated air through the supplementary compartment, openings may be provided in the top and bottom walls 16 and 17. If desired, ventilating openings may be provided in the side walls 15 of the casing at opposite ends of each of the shelves so as to produce sufficient exchange of air to prevent sweating. This may be accomplished by omitting the pins 46 and striking inwardly the metal of the walls 15 to form lugs, or if desired louvres, adapted to cooperate with the slots 45 to support the shelves. By thus forming inwardly projecting lugs from the metal of the wall to replace the pins 46, openings will at the same time be provided for ventilation purposes.

I claim:

1. In a refrigerator cabinet having an outer door, an inner main compartment, a box-like casing open at one side facing said door and hinged to swing through the door opening, said casing forming an outer compartment, and yielding means between said casing and a wall of the cabinet for limiting the inward swinging movement of the casing and effective to clamp the casing in position within said main compartment.
2. In a refrigerator cabinet having an inner compartment, an outer door, an outwardly swinging casing forming a supplementary compartment adjacent the inner face of the door, vertically aligned pivot members mounted at the top and bottom of the casing for swingingly supporting the casing within said inner compartment, one of said pivot members being spring pressed in the direction of the adjacent cabinet wall.
3. In a refrigerator cabinet having an inner compartment, an outer door, an outwardly swinging casing forming a supplementary compartment adjacent the inner face of the door, vertically aligned pivot members mounted at the top and bottom of the casing for swingingly supporting the casing within said inner compartment, one of said pivot members being spring pressed in

the direction of the adjacent cabinet wall and also retractable to permit bodily removal of the casing.

4. A domestic refrigerator comprising a cabinet having a main inner compartment and a main door opening, a movable outer door of a size to close said opening, an auxiliary food compartment associated with said door in rear thereof and including a casing having a rear vertical wall and enclosing forwardly extending side walls adapted to effect an approximate closure of said opening and to expose said food compartment when the outer door is open, said casing being movable horizontally through said opening independently of the door, and a releasable latching device interposed between one of said casing side walls and the adjacent cabinet side wall and co-operable therewith for maintaining the auxiliary food compartment in fixed relationship with respect to the cabinet when the outer door is opened.

5. A domestic refrigerator comprising a cabinet having a main inner compartment and a main door opening, a movable outer door of a size to close said opening, an auxiliary food compartment associated with said door in rear thereof and including a casing having a rear vertical wall and enclosing forwardly extending side walls adapted to effect an approximate closure of said opening and to expose said food compartment when the outer door is open, said casing being movable horizontally through said opening independently of the door, a projecting flexible non-metallic strip carried by said casing and engaging the main door opening when the casing is in closed position to thereby seal said main compartment, and a retainer portion carried by and adjacent an edge of one of the casing side walls for securing said strip to the casing.

6. A domestic refrigerator comprising a cabinet having a main inner compartment and a main door opening, a movable outer door of a size to close said opening, an auxiliary food compartment associated with said door in rear thereof and including a casing having a rear vertical wall and enclosing forwardly extending side walls adapted to effect an approximate closure of said opening and to expose said food compartment when the outer door is open, said casing being movable horizontally through said opening independently of the door, and a projecting flexible sealing strip carried by and extending along an edge of one of the casing side walls and adapted to engage the main door opening to seal the main compartment, said edge having a coiled portion forming a retainer for said strip.

7. In a refrigerator cabinet having an inner main compartment, a pair of outwardly swinging inner and outer doors, the inner door having a supplementary compartment accessible at the front face thereof and comprising a back wall and forwardly extending enclosing side walls, and a wire formed shelf detachably mounted within said supplementary compartment and including opposed end portions adapted to be relatively compressed between said side walls to hold the shelf firmly in position against vibration, said side walls and said end portions having releasable interlocking means.

ALBERT P. BALL.
